UNITED STATES PATENT OFFICE.

MARK N. RUSSELL, OF SYRACUSE, NEW YORK, ASSIGNOR TO PASS & SEYMOUR, INC., OF SYRACUSE, NEW YORK, A CORPORATION OF NEW YORK.

LAMP GRIP.

Application filed March 7, 1925. Serial No. 13,912.

This invention relates to sockets for incandescent lamps or for fuses or like objects which are threaded into the screw shell of the socket which forms one of the electrical 5 terminals.

It is a general object of this invention to provide in a screw shell socket a novel and improved means for retaining lamps or the like therein in a more positive manner.

More particularly it is an object of this invention to provide a friction device or lamp grip means associated with the screw shell of the socket to frictionally engage the threads on the base of the lamp or other device 10 vice to retain the center contact thereof in engagement with the center contact of the socket.

In the accompanying drawing and the following specification there is disclosed by 20 way of example, only, a single embodiment of the present invention with the understanding, however, that various modifications and changes may be made in the size, form, proportion, material and arrangement 25 of the various parts without departing from the scope of the attached claim.

In said drawings Figure 1 is a side elevation partially in central longitudinal section through a socket constructed according to 30 this invention.

Figure 2 is a transverse section through the screw shell of the socket, and

Figure 3 is a longitudinal central section through the screw shell taken in a plane at 35 right angles to that shown in Figure 1.

In using the ordinary form of screw socket for lamps, fuses, attachment plugs and other similar devices, it has been found that there is sometimes a tendency for the 40 lamp or other object to become loosened so that the electrical contact between the center button on the base of the lamp and the center contact of the socket is very poor or entirely broken. In the former case, arcing or 45 heating of the respective parts may result, whereas in the latter case the circuit to the lamp or other object is open and it will not operate. This condition is exaggerated where the socket and its associated part is 50 subject to considerable vibration such as in tall buildings or around machinery, on street cars, etc. The use of socket switches of the various types may also aggravate this condition and it therefore has been found 55 desirable to provide some means to more

securely retain the lamp or the like within the socket and yet which, at the same time, will not necessitate an undue twist being given the lamp or the like which may result in loosening the base thereof. The device 60 of the present invention has been designed to overcome these difficulties in an extremely simple manner.

Referring to the drawings, there is shown in Figure 1 a common form of incandescent lamp socket including the outer shell 10, the cap 11, the insulating button 12, the insulating lining 13, the screw shell 14 and the center contact 15, all of which are well-known. Any form of socket switch may be 65 provided if desired. At 16 is shown an incandescent lamp having the threaded base 17 and the center contact 18 insulated therefrom. The base 17 of the lamp is usually so proportioned as to fit loosely within the 70 threaded shell 14 of the socket, reliance being placed upon the frictional engagement of the respective threads with each other, due to the contact between the parts 15 and 18 to retain the lamp in position. In order 75 that this frictional engagement may be sufficient to prevent the lamp from jarring loose and thus reducing the effectiveness of the electrical contact between the parts 15 and 18, it is necessary that the lamp be screwed 80 quite tightly into the socket, which may result in breaking the shell 17 loose from the lamp 16, since the connection between these 85 two parts is effected by a cement. Such loosening of the threaded shell from the lamp may render it useless, since a subsequent twist of the lamp in respect to the shell may twist the two lead wires within the base and short-circuit them.

The present invention contemplates over- 90 coming these difficulties by providing the grip member 19 which is attached to the inner face of the screw shell 14 by means of the tabs or ears 20 formed integral with the grip member and bent over the ends of 95 the screw shell 14. This grip member 19 comprises, merely, a narrow rectangular strip of spring metal slightly bowed to expose its convex face for contact with the tops of the threads on the lamp base 17.

To provide accommodation for this grip member 19 the screw shell 14 which is formed of quite thin metal, rolled or pressed into the threaded form shown, is provided with a longitudinal channel 21 pressed into 100

its inner face to such a depth as to receive the grip member 19 with its inner surface, when in a flattened or non-bowed condition, slightly above the bottoms of the threads in 5 the screw shell 14. This is clearly shown in Figure 2 which is a section transverse to the screw shell taken near the middle of the grip member, and it will be noticed that the center portion of the grip member is 10 bowed outward toward the center of the screw shell so as to more readily engage the tops of the threads on the lamp base in spite of slight variations in the size of the bases made by different manufacturers.

15 In using the device it provides an easy but positively frictional engagement between the threads of the lamp base 17 and those of the screw shell 14 by forcing the side of the base remote from the grip member 20 against the opposite inner wall of the screw shell. At the same time the grip member provides adequate frictional engagement with the tops of the threads on the lamp base 17, which, if it is large enough, 25 presses on the central bowed portion of the grip and flattens it down into the channel 21 made to receive it. The walls 22 of the channel 21 engage with the edges of the grip member 19 and prevent it from being rotated in either direction when the lamp is 30 being placed in or removed from the socket and the end tabs 20, loosely bent over the ends of the shell, prevent any longitudinal movement of the grip member.

It has been the usual practice to make 35 the center contact 15 resilient or in the form of some sort of spring, in order that it may be partially compressed when the lamp is screwed into the socket so that in case any vibration loosens the lamp this spring contact 40 will follow the center button 18 on the lamp for some distance and still remain in contact with it. With the present construction, however, it is possible to eliminate the 45 spring from the center contact 15 since the lamp grip means serves to positively retain the center contact of the lamp against the center contact of the socket. This results in a cheaper construction, since it is not necessary to use expensive spring material 50 or as complicated a structure for a solid center contact as for a spring contact, and furthermore there is even less possibility of loosening at this point.

Having thus described my invention, what 55 is claimed as new and desired to be secured by United States Letters Patent is:

A lamp socket comprising an insulating base, center and screw shell contacts supported thereby, said shell contact having a 60 longitudinally extending channel on the interior thereof, a bowed spring in said recess and ears on said spring engaging over the edges of said shell to retain the spring in 65 said channel.

In testimony whereof I hereunto affix my signature.

MARK N. RUSSELL.
